TENDERIZING CASINGS

Floyd L. Kauffman, Palos Park, and Walter M. Urbain, Western Springs, Ill., assignors to Swift & Company, Chicago, Ill., a corporation of Illinois

Application April 20, 1950, Serial No. 157,140

7 Claims. (Cl. 99—175)

1

The present invention relates to a novel method and apparatus for effecting tenderization of natural casings. More specifically, the invention relates to a novel method and apparatus for effecting the tenderization of natural casings, either stuffed or prior to stuffing, by treatment with ultra-violet light.

Natural casings, as distinguished from artificial or synthetic casings, are prepared from the intestines of edible animals such as cattle, swine and sheep. After the intestines have been removed from the carcass, they are cleaned, and a tubular membrane appropriate for sausage casings is obtained. Domestic sheep casings are normally much more tender than hog, beef, or Indian sheep casings, and usually do not require tenderizing. However, hog casings and Indian sheep casings, which could be used in the manufacture of frankfurters and other sausages similar in size, are not normally acceptable for such purpose because of their natural toughness, which renders them difficult to masticate and digest.

The present invention contemplates the treatment of natural casings prepared from edible animal intestines with ultraviolet radiation, with an appreciable portion of the radiation having a wave length falling in the range of about 1800 to 2500 angstrom units. It has been found from actual tests that normally tough hog casings, for example, can be tenderized very quickly and economically by exposing all portions of the same directly and preferably at short range to the action of an ultraviolet radiator for a period of time, depending on the output of the radiator and the particular distance. It has also been found that stuffed natural casings such as hog casings, for example, can be tenderized by a similar treatment prior to smoking. It has further been found that ultraviolet light improves the tenderness properties of sausages, such as frankfurters, after they have been smoked, usually requiring considerably more ultraviolet energy for tenderizing than for similar unsmoked sausages.

Natural casings have been tenderized heretofore by the use of certain enzyme solutions, as disclosed in the patent to Ramsbottom et al., 2,321,622, dated June 15, 1943. In contrast with the Ramsbottom et al., method the present method does not require the application of any enzyme or other solution to the surface of the casings. Nor does it require any special temperature or humidification conditions of the atmosphere within the treating room and, hence, affords great economical possibilities.

Accordingly, the principal object of the invention is to impart such properties to a normally tough natural casing as will render the same easy to masticate and digest.

An important object of the invention is to provide a method and apparatus whereby normally tough animal casings may be quickly tenderized

2

to a desired substantial degree without material disintegration.

Another important object of the invention is to provide a quick and economical method of tenderizing natural casings and which method does not require the application of any treating solutions or any special temperature or humidification conditions of the atmosphere within the treating chamber.

A more specific object of the invention is to provide a method whereby normally tough casings, such as hog casings, beef, and Indian sheep casings, may be tenderized and thus rendered useful in the manufacture of high grade frankfurters and other sausage products requiring a tender casing.

Other objects and advantages of the invention will be apparent from the following description taken in conjunction with the accompanying drawing, in which:

Figure 1 diagrammatically illustrates a simple type of apparatus that may be employed for tenderizing unstuffed, natural casings;

Figure 2 is an enlarged sectional view taken on the line 2—2 of Figure 1;

Figure 3 diagrammatically illustrates an apparatus similar to that of Figure 1, except that it is modified so that it may be employed for tenderizing stuffed, natural casings;

Figure 4 is a plan view of one form of apparatus for practicing the process of the invention in a continuous manner;

Figure 5 is a side view partly in section of the apparatus shown in Figure 4;

Figure 6 is a vertical section along the lines 6—6 of Figure 5;

Figure 7 is a view of an ideal arrangement of lights for producing maximum theoretical exposure of the product;

Figure 8 is a plan view of a modified type of apparatus adapted for treating sausages arranged on smoking sticks;

Figure 9 is a side view of the tenderizing conveyor shown in Figure 8;

Figure 10 is a vertical section taken along the line 10—10 of Figure 8;

Figure 11 is a graph showing the per cent change in tenderness of casings as measured by a penetrometer plotted against the time of exposure to ultraviolet light; and

Figure 12 is another graph similar to the graph in Figure 11, showing a comparison of unsmoked and smoked casings.

Referring now to Figures 1 and 2, the numeral 1 generally indicates a source of ultraviolet light including an elongated tube 2 and a reflector 3. Such light source may be a 360 watt Uviarc ultraviolet lamp, for example. A stick 4 of wood or other suitable material is provided with a hook 5 secured to one end thereof. The hook 5 is adapted to cooperate with a hook 6 which may

be fastened to one end of a driven shaft 7. A pulley 8 may be mounted upon the shaft 7 and driven by a belt 9. A suitable length of unstuffed natural casing 10 is threaded onto the rod 4 and then the rod 4 is hung by the hook 5 from the hook 6 in substantial parallelism with and about 5 inches from the ultraviolet light tube 2, as indicated in Figure 2. The shaft 7 is adapted to be slowly rotated at about 30-120 R. P. M. by the belt 9, and pulley 8 by any conventional or suitable means (not shown).

Preparatory to tenderization, the casings are washed and rinsed to effect removal of salt, etc., and a suitable length is then threaded onto the rod 4, which is then hung from the hook 6 and slowly rotated in the manner described in order to expose the casings while in a moist condition to ultraviolet light having a wave length specified therein. When a single ultraviolet light tube 2 is used, only about one-third of the exterior surface of the casing 10 is exposed to the direct rays of the ultraviolet light at any given instant; hence, the actual time that a particular section of the casing 10 is exposed to the direct rays of the ultraviolet light is approximately one-third of the total time that said casing is rotated. In this manner, longitudinal portions of the casing 10 are progressively exposed to the rays of the ultraviolet light emanating from the tube 2. While some slight heating may result, this has a negligible effect on the tenderization of the casings as will be evident from Table I. Moreover, the exposed portions are continuously cooled by the surrounding air of the treating room before being again exposed to the light rays on the next revolution of the shaft 7. Thus, portions of the casing 10 are intermittently exposed to the action of the ultraviolet light rays. The degree of tenderization can be varied by altering the time interval of exposure, as will appear more fully hereinafter.

The actual amount of tenderization of the casing 10 effected by the treatment with the ultraviolet light may be determined by the use of a penetrometer which measures the force necessary to puncture a stuffed casing with a steel ball. The penetrometer constitutes no part of the present invention, but as a matter of information, it comprises a steel ball having a diameter of $\frac{1}{8}$ inch mounted upon a rod of smaller diameter operatively attached to a suitable gauge. The penetrometer gauge is arbitrarily calibrated so that one unit corresponds to one-twentieth of a pound, the entire gauge scale including graduations from 1 to 200. In order to obtain representative readings, an average of a number of readings (50 to 100) is used for each test. In all cases, the experimental control, or comparison test specimen, consists of an untreated portion of a casing, the remainder of which is treated to ascertain the tenderizing effected by a given exposure to ultraviolet light.

The following tabulation, identified as Table I, shows average penetrometer readings for unstuffed hog casings exposed to various light sources such as a 360 watt Uviarc ultraviolet lamp (with and without a 970 Corex filter) and a 260 watt infra-red lamp. In each instance, the casing was positioned approximately 5 inches from the lamp. In making the ultraviolet light treatments, the casings were stretched over a small glass rod and hung parallel to the tube of an ultraviolet lamp equipped with a reflector. The infra-red treatment was made by stationing the infra-red lamp equipped with a reflector at

right angles to the casing which was likewise fitted over a glass rod. During treatment with the lights, the casings were rotated slowly by mechanical means. The time of exposure, as listed below is the total time the casing was exposed to the light. As only about one-third of the casing was exposed at one instant, the actual time the particular section was exposed to the light was approximately one-third of the time listed.

TABLE I

Light	Time of Exposure in Minutes	Penetrometer Readings			
		Control	After Exposure	Diff.	Average Diff.
360 Watt Uviarc	3	{ 65.4 70.2	{ 53.2 54.4	{ 12.2 15.8	{ 13.0
Filtered (970 Corex)	5	{ 58.8 72.3	{ 47.8 74.5	{ 11.0 -2.2	{ (-2.2)
360 Watt Uviarc	10	70.9	72.9	-2.0	(-2.0)
260 Watt Infra-Red	3	65.4	64.7	0.7	(0.7)
	5	62.3	60.4	1.9	(1.9)

In addition to indicating the various types of ultra-violet, etc., lamps employed, Table I indicates the time of exposure in minutes in rotating test specimens, the toughness of the control specimen as determined by the penetrometer, the toughness of the treated casing after exposure, the difference between the penetrometer readings of the casing material before and after exposure, and the average difference in toughness of the several casings tested. The data show that substantial tenderization occurs as a result of the treatment with the ultraviolet light. The data for the treatment with the filtered light of the Uviarc lamp show no tenderization, the wave length of this filtered light being substantially entirely above 2800 angstrom units. Treatment with the infra-red lamp indicates that tenderization is not due to heat as shown by the fact that no appreciable lowering of the penetrometer readings was observed after the casings were exposed to the heat rays of said lamp.

In Table II, the relationship between the degree of treatment as expressed in time or total energy and the amount of tenderizing is shown. The data were obtained by exposing hog casings in a manner similar to that described for the treatment shown in Table I. Also, the samples were rotated as before; the data given for the time of exposure and the total energy in microwatts per square centimeter represent the actual treatment of the casings at any given point. They are calculated as one-third of the total time of exposure and are one-third of the total microwatts emitted during the entire time of rotation.

TABLE II

Actual Time of Exposure	Microwatts per sq. cm.	Penetrometer Readings			
		Before Exposure	After Exposure	Diff.	Percent Diff.
3.33 sec.	15,900	45.0	45.4	+0.4	+0.9
6.67 sec.	31,800	66.4	66.3	-0.1	-0.2
10.0 sec.	47,600	66.4	64.4	-2.0	-3.0
20.0 sec.	95,500	45.0	41.3	-3.7	-8.2
40.0 sec.	191,000	63.5	54.3	-9.2	-14.4
60.0 sec.	282,000	65.4	53.2	-12.2	-18.7
3.33 min.	476,000	62.3	45.1	-17.2	-27.6
6.67 min.	955,000	62.3	44.6	-17.7	-28.4
10.0 min.	2,820,000	62.3	50.5	-11.8	-19.0

The data tabulated in Table II is shown graphically in Figure 11 wherein the time of exposure is plotted against the per cent change in penetrometer readings. It will be observed from the curve that the tenderizing effect reaches a maximum at a time of exposure of about 5 minutes which represents a total energy of 1,432,000 microwatts per square centimeter.

After about 6 minutes' exposure there is a definite toughening of the casing as shown in Figure 11. In other words, the tenderizing effect reaches a maximum at around about 4 minutes to 6 minutes and thereafter there is a falling off of the tenderizing effect. The decrease in the tenderizing effect may be due to dehydration of the casing since such dehydration can be observed from the dry appearance of the casing.

In calculating the total energy listed above, use was made of published data on the ultra-violet light source. The radiator was used according to the directions of the manufacturer so that the energy output and the spectral distribution of the energy output could be expected to be identical with the measurements made by the manufacturer. The reflectors supplied with the lamps were used. In determining the energy falling on a square centimeter of surface two additional quantities were needed. These were the time for which the lamp was operated and the distance between the object and radiator. The latter quantity affects the amount of energy falling on a unit area according to the inverse square law. Other factors being constant, this law applies and may be stated as follows:

$$\frac{E_1}{E_2} = \frac{D_2^2}{D_1^2}$$

where E_1 and E_2 are the energies and D_2 and D_1 are the distances between the object and radiator. In this law the assumption is made that the radiator is a point radiator. The ultraviolet sources used here have physical dimensions and are not points; consequently, the law stated above applies only approximately and deviations from it becomes greater as the distance between the object and radiator becomes smaller.

The method of calculation may be illustrated by the following example. The energy given off by a 360 watt Uviarc lamp between 1800 and 2500 angstroms is 77 microwatts per second per square centimeter at one meter when operating according to the directions of the manufacturer. If this lamp were used at a distance of 5 inches or 0.127 meter for one minute the total energy falling on a square centimeter would be calculated as follows:

$$\frac{77}{E_2} = \frac{.127^2}{1^2}$$

E₂ equal 4,770 microwatts per second per square centimeter or in 60 seconds 280,000 microwatts per square centimeter.

The exact theory or explanation of the phenomenon of tenderization by ultraviolet light is not known, but by way of possible explanation, and not by way of restriction or limitation, it is believed that the radiant energy of ultraviolet wave lengths lying between about 1800 and 2500 angstrom units produces denaturation of the protein, that is, a change of state of protein from the natural state by some such action as coagulation, oxidation, or breakage of atomic linkages of the protein molecules, whereby the tissues are weakened and tenderization occurs. The Uvilarc lamp provided with a Corex filter for eliminating wave lengths below about 2800 ang-

strom units produced no improved tenderization of the casings. The lamp without a filter emits wave lengths as low as 1800 angstrom units and definitely does produce tenderization. Also, when casings are subjected to radiation from an ultra-violet sterilization lamp, such as used in quick-agaging meat, which emits practically no radiation having a wave length below 2500 angstroms (see James Patents 2,169,081 and 2,192,348), the casings are not tenderized even after prolonged exposure to the radiation from such an ultra-violet sterilization lamp. Therefore, the active wave length which is effective for tenderizing casings in accordance with the herein disclosed process is in the range of between about 1800 and 2500 angstrom units.

Figure 3 illustrates the manner in which stuffed casings may be tenderized by exposure to ultraviolet light. As illustrated, a stuffed casing 10^a, prior to linking and smoking, is suspended from the hook 6 in substantial parallelism with the ultraviolet light tube 2 and is slowly rotated with the shaft 1.

In Table III are shown data obtained by treating stuffed hog casings with radiation from a 1200 watt Uviarc ultraviolet lamp. The sausages were located 5 inches distant from the radiator and were slowly rotated. The time of exposure and the penetrometer readings were determined as described heretofore in connection with Table II. In both the control and the irradiated samples the sausages were completely processed prior to making the penetrometer readings. The processing comprised cooking and smoking so that a finished product was obtained according to commercial practice.

TABLE III
Effect of exposure to the 1200 watt Uviarc at 5
inches upon unsmoked frankfurters

Actual Time of Exposure	Micro-watts per sq. cm.	Penetrometer Readings

65						67.6

The data in Table III is shown also in the form of a curve in Figure 12. It will be observed that the tenderizing effect reaches a maximum at around 5 minutes and a total energy of 11,100,000 microwatts. The data show that stuffed casings may be satisfactorily tenderized. The stuffed casings are more easily handled and are preferred for treatment from a practical standpoint rather than the unstuffed casings.

It has been found that stuffed casings may also be tenderized after smoking. From a practical standpoint this is the most desirable form for treatment although the total energy requirements are somewhat increased.

In Table IV data are given for the treatment of smoked and stuffed hog casings using a 1200 watt Uviarc ultraviolet lamp, with the sausages 5 inches distant from the lamp. The sausages were rotated and the time of exposure and total energy determined as described heretofore. The data in Table IV are also shown in the form of a curve in Figure 11.

TABLE IV
Effect of exposure to the 1200 watt Uviarc at 5 inches upon smoked frankfurters

Time of Exposure min.	Micro- watts per sq. cm.	Penetrometer Readings			
		Before Expo- sure	After Expo- sure	Diff.	Percent Diff.
1.0	2,220,000	137.9	106.5	31.4	22.9
1.33	2,960,000	90.5	65.3	25.0	27.6
2.5	4,440,000	137.9	98.2	39.7	28.8
3.	6,660,000	112.9	57.9	55.0	48.8
6.	13,320,000	112.9	48.1	64.8	57.4
12.	26,640,000	112.9	50.0	62.9	55.8

The data of Table IV, show that the stuffed and smoked casings are more difficultly tenderized than the stuffed and unsmoked casings. The total energy requirements are higher for treating the smoked casings and also the maximum degree of tenderizing is lower for the smoked casings. For example, it will be observed from Figure 12 that in order to secure a 50 per cent change in the penetrometer readings of the unsmoked casing a total of about 2,660,000 microwatts are required; whereas for the smoked casing a total energy of about 7,330,000 microwatts are required. Furthermore, the maximum percentage change in penetrometer readings for the unsmoked casing was around 67 as compared with a maximum of about 57 for the smoked casing. Although the smoked casings are more difficult tenderized, the desirability of treating the smoked casings often offsets the difficulty in the tenderizing. The treatment of smoked casings accordingly is a modification contemplated within the scope of the present invention.

While the above data were obtained with two different lamps, namely, a 360 watt Uviarc and a 1200 watt Uviarc, the selection of the lamp was merely a matter of experimental convenience. The 360 watt lamp is somewhat easier to manipulate in experimental work and was used when convenient. However, in the case of the stuffed and the stuffed and smoked casings, it was found that the 1200 watt lamp was more desirable because of the expediency of using a higher intensity on these casings and because the lamp emits a greater proportion of ultraviolet light having a wave length between 1800 and 2500 angstrom units. The invention is not restricted to the use of lamps of any particular wattage and we contemplate using lamps of wattages from 360 to 4500, which are the currently commercially available lamps. Moreover, the invention is not restricted to any particular type of lamp, the object being to secure radiation of certain characteristics regardless of the source. For example, we may use an open arc, such as a carbon arc or an iron arc,

instead of the mercury vapor lamp. Other lamps contemplated for use instead of a Uviarc are any one of the Hanovia high pressure quartz mercury arc lamps, the choice of the particular wattage being determined by the specific installation intended.

The 360 watt fused quartz mercury arc lamp or Uviarc lamp employed in the above experiments has an arc length of about 6 inches maximum, a rating of 54 watts per arc inch, and develops 77 microwatts of ultraviolet energy (1800 to 2500 angstroms) per square centimeter at 1 meter. It has an overall length of 10 $\frac{1}{8}$ inches and a diameter of $\frac{3}{4}$ inch maximum. The radiation characteristics of the lamp are as follows:

TABLE V

Regions (Wave Length = Å.)		Approximate Microwatts Per Sq. Cm. at 1 Meter Distance from Lamp
Far Infrared: Red: 25,000-14,000		47
Near Infrared: 14,000-7,000		95
Visible: 7,000-4,000		299
Near Ultraviolet: 4,000-3,100		237
Middle Ultraviolet: 3,100-2,800		91
Far Ultraviolet: 2,800-2,500		116
2,500-2,200		48
2,200-1,850		29

The 1200 watt Uviarc lamp used in the above experiments is a fused quartz mercury arc lamp having the following characteristics:

TABLE VI
Electrical data

Arc watts	1200
Arc length (inches)	12.5
Inside diameter (inches)	0.7
Volts	350
Amperes	4

Radiation characteristics

Wavelength, angstroms	Microwatts per sq. cm. at 1 Meter
5,600-4,000	1,563
4,000-3,100	1,131
3,100-2,800	469
2,800-2,500	457
2,500-1,850	615

The 1200 watt tube develops about 615 microwatts per square centimeter of active ultraviolet radiation (1850-2500 angstroms) at 1 meter. The above characteristics, including power consumption and ultraviolet radiation output, demonstrate that this tube is a high intensity source of ultraviolet radiation below 2500 angstroms.

Figures 4 to 10 show forms of apparatus intended for adapting the invention to commercial practice. One modification is shown in Figures 4 to 7, inclusive, and another modification is shown in Figures 8 to 10, inclusive.

Referring to Figures 4 and 7, the numeral 12 represents a conventional stuffing and linking table. Animal casings such as sheep or hog casings may be stuffed on a stuffing horn, not shown, and the stuffed casing separated into links by hand or by a mechanical linking machine, also not shown. The string of sausages, which may be frankfurters or pork sausage, is delivered onto the table 12. The string of sausages 14 may then be arranged, for example, by an operator upon a smoking stick 15. The smoking stick loaded with

the sausages is then placed on the hooks 18 of a continuous conveyor 20. The conveyor 20 is mounted on shafts 21 and 22 and is adapted to convey the sausages through an ultraviolet light chamber 24 wherein the sausages are exposed to ultraviolet light radiating from lamps 25. The lamps are preferably arranged in circular form around the conveyor as shown in Figure 6 so that the lamps are substantially equidistant in all directions from the sausages and the rays strike the sausages on all sides.

An ideal arrangement which is desired to be approached as nearly as possible is shown in Figure 7. A near approach to this ideal arrangement may be obtained by laying the frankfurters lengthwise on the conveyor instead of hanging them on smoking sticks from the hooks. A modification in which the frankfurters are laid lengthwise on the conveyor is shown at the top of Figure 7. In this way the frankfurters pass in a substantially horizontal straight line between the lamps and the ideal condition as to equidistance on all sides from the lamps, and complete exposure of the entire surface of the frankfurters to the light rays is more nearly approached. Since the degree of tenderization is dependent upon the total energy of the ultraviolet rays striking the surface of the sausages, it is important that uniform exposure of the casings be obtained. It is intended that the lights be arranged in such positions and at such distances from the sausages that rays of substantially equal intensity strike the entire surface of the sausage casings at the same time. The arrangements of sausages during exposure to the ultraviolet rays are merely illustrative, and other means and methods of exposing the casings to accomplish the desired results may be used.

After the ultraviolet light treatment the sausages may be removed from the conveyor by an operator and placed on a smoking tree 26 preparatory to placing the sausages in smokehouses. If the sausages have already been arranged on a smoking stick, as shown in Figure 5, all that is necessary for the operator to do is to remove the sausage sticks from the hooks on the conveyor and transfer them to the smoking tree. In case the sausages are conveyed in tandem between the lights, as shown in Figure 7, it may be necessary for the operator to remove the string of sausages from the conveyor and arrange them on the smoking sticks which are then placed on the smoking tree.

Figures 8, 9, and 10 show a modified form of apparatus wherein the smoking sticks loaded with the sausages are arranged crosswise of the conveyor instead of parallel to the conveyor. This modification has certain advantages in securing more uniform exposure of the surfaces of the sausages to the ultraviolet light. As shown in the drawings, two stuffing and linking tables 31 and 32 may be provided for feeding the frankfurters to the ultraviolet light chamber 35. In this modification, the conveyor is made up of two parallel chains or belts 36 and 38. A series of sausage sticks 40 may be mounted crosswise of the conveyor chains. The sausages are carried by the conveyor past the ultraviolet lights 42, the speed of the conveyor being correlated with the length of the lights so that the proper time of exposure of the sausages to the ultraviolet rays is secured. It will be observed that the lights are arranged above and below the upper flights of the conveyor and the upper and lower group of lights are offset, as shown in Figure 10, so that substantially uniform exposure of the sausages results. The con-

veyor is driven by a motor 43 which is connected by a drive chain 44 to drive shaft 45 of the conveyor. In this modification, the smoking sticks are removed from the conveyor after passing through the ultraviolet light chamber and may be placed on a smoking tree shown diagrammatically in Figure 8 and represented by the numeral 46.

In practicing the invention, the conditions under which the casings may be tenderized may vary considerably, depending upon the character of the product; that is, whether it is an unstuffed, a stuffed, or a stuffed and smoking casing. Certain general conditions, however, may be stated as permissible and preferred operating ranges. The distance of the radiator from the casing will not vary with the different products treated. It is desirable to bring the radiator as close to the product as possible without heating or burning so as to avoid dehydrating the casing. We contemplate using the lamp at a distance of about 1 inch to 5 inches and preferably at a distance of around 5 inches. In practice the distance would be governed by the physical size of the radiators, the number of radiators, and the space relationship between the casings and the radiator or radiators.

The time of treatment with the ultraviolet rays will depend somewhat on the capacity of the unit desired. In general, it may be said that as short a time as possible is generally preferred. We contemplate, for example, using a time of about 10 seconds to 30 seconds, although longer time periods, for example, up to several minutes, may be used. It will be appreciated that the time is related to the total energy which in turn depends on the size and number and the distance of the lamps from the object. The factors of time, distance, and the energy output determine the total energy. In general, however, we contemplate using total energies as indicated in Table VII, wherein operating and preferred ranges of total energy microwatts per square centimeter are given for unstuffed, stuffed, and stuffed and smoked casings.

TABLE VII

Product	Microwatts per sq. cm.	
	Operating Range	Preferred Range
Casings	100,000-2,000,000	200,000-1,000,000
Stuffed Casings	100,000-15,000,000	200,000-4,000,000
Smoked Frankfurts	1,000,000-30,000,000	2,000,000-14,000,000

The casings useful in the present invention include freshly prepared casings and those which have been salted and stored under refrigeration for some time. The salted casings are washed prior to tenderizing to remoisten. The casings are treated in a moist condition but excess moisture is undesirable because of absorption of light rays by the water.

It will be understood that various means may be used to support the unstuffed or the stuffed casings relative to the source of ultraviolet light, that the distance between the light source and the casings to be treated may be varied within reasonable limits from the distance specifically disclosed herein, and that various types of ultraviolet light lamps of different wattage from that disclosed herein as an operative example may be employed.

This is a continuation-in-part of application Serial No. 542,458, filed June 28, 1944, now abandoned.

11

Obviously, many modifications and variations of the invention hereinbefore set forth may be made without distinguishing from the spirit and scope thereof, and therefore, only such limitations should be imposed as are indicated in the appended claims.

We claim:

1. The method of quickly tenderizing natural casings, which comprises: exposing all portions of the exterior surface of said casings while in a moist condition to the direct action of ultraviolet light of about 360 to 4500 wattage emitting radiation having a wave length in the range of 1800 to 2500 A. U. for a period of about 10 seconds to several minutes at a distance of about one to five inches whereby the casings are tenderized.

2. The method of quickly tenderizing natural casings, which comprises: exposing all portions of the exterior surface of said casings while in a moist condition to the direct action of ultraviolet light having a wattage of about 360 and an active wave length in the range of 1800 to 2500 A. U. for a period of about 10 seconds to six minutes with said casings positioned about one to five inches from the source of said ultraviolet light whereby the casings are tenderized.

3. The method of tenderizing natural casings, which comprises the steps of: subjecting all portions of the exterior of the said casings while in a moist condition at a distance of about five inches from a source of ultraviolet light having a wattage of about 1200 and an active wave length in the range of 1800 to 2500 A. U., and maintaining said exposure for a period of about 10 to 30 seconds whereby the casings are tenderized.

4. The method of quickly tenderizing natural casings, which comprises: exposing all portions of the exterior of the said casings while in a moist condition to the action of an ultraviolet light source emitting waves of a length in the range of 1800 to 2500 A. U. and maintaining the exposure of the said casing to the action of said ultraviolet light to apply about 100,000 to 30,000,000 microwatts of energy from the said light source per square centimeter of casing surface area within a period not substantially in excess of about 6 minutes.

12

5. The method of treating unstuffed natural casings to tenderize the same, which comprises: subjecting all portions of the exterior of the said natural casings while in a moist condition to radiation from an ultraviolet light source having an active wave length in the range of 1800 to 2500 A. U., and maintaining the exposure of the said casings to the action of the said radiation to apply about 100,000 to 2,000,000 microwatts of energy from the said light source per square centimeter of casing surface area within a period not substantially in excess of about 6 minutes.

6. The method of treating a stuffed, unsmoked natural casing to tenderize the same, which comprises: subjecting the stuffed casing while in a moist condition to exposure on all sides from a source of ultraviolet light, said source having an active wave length in the range of 1800 to 2500 A. U., and maintaining said exposure to apply about 100,000 to 15,000,000 microwatts of energy from the said light source per square centimeter of casing surface area within a period not substantially in excess of about 6 minutes.

7. The method of treating a stuffed, smoked natural casing to tenderize the same, which comprises: exposing all portions of the exterior of the said stuffed and smoked casing while in a moist condition to a light source emitting light having an active wave length in the range of 1800 to 2500 A. U., and maintaining said exposure to apply about 1,000,000 to 30,000,000 microwatts of energy from the said light source per square centimeter of surface area of the casing within a period not substantially in excess of about 6 minutes, whereby the casings are tenderized.
